UNITED STATES PATENT OFFICE.

JOHN L. KAHLES, OF OAKLAND, CALIFORNIA.

DESIGN FOR A TABLE AND DESK TOP.

49,966.

Specification for Design.

Patented Nov. 28, 1916.

Application filed September 8, 1916. Serial No. 119,119. Term of patent 7 years.

To all whom it may concern:

Be it known that I, JOHN L. KAHLES, a citizen of the United States, residing at Oakland, in the county of Alameda and State of California, have invented a new, original, and ornamental Design for a Table and Desk Top, of which the following is a specification, reference being had to the accompanying drawing, forming part thereof.

The figure is a face view of a desk and table top, showing my new design.

I claim:

The ornamental design for a desk and table top, as shown.

JOHN L. KAHLES.

Witnesses:

A. Z. ROGERS,
F. T. WOOD.
